O. R. ERWIN

FIRE EXTINGUISHING APPARATUS

Original Filed Dec. 20, 1920

Inventor
Orlando R. Erwin,
By his Attorneys
Meyers, Cavanaugh & Hyde

UNITED STATES PATENT OFFICE.

ORLANDO R. ERWIN, OF FOREST HILLS, NEW YORK, ASSIGNOR TO FOAMITE-CHILDS CORPORATION, OF NEW YORK, N. Y., A CORPORATION OF DELAWARE.

FIRE-EXTINGUISHING APPARATUS.

Application filed December 20, 1920, Serial No. 431,923. Renewed November 23, 1923.

To all whom it may concern:

Be it known that I, ORLANDO R. ERWIN, a citizen of the United States, and resident of Forest Hills, in the county of Queens 5 and State of New York, have invented certain new and useful Improvements in Fire-Extinguishing Apparatus, of which the following is a specification.

This invention relates to a fire extinguishing apparatus, and more particularly to a fire extinguishing apparatus of the foam producing type, and has special reference to the provision of an apparatus of this type designed so as to be capable of being 10 set into operation to generate foam and develop sufficient pressure to deliver the foam to relatively high elevations as is required for example for oil tank protection.

A principal object of my present invention comprehends the provision of a foam producing fire extinguishing apparatus embodying a self-contained unit having a simple organization of parts especially suited and readily installable for protecting isolated regions at low cost. For isolated regions such as segregated oil tanks, the cost of installing and operating a fire extinguishing system in which a pumping means or the like is utilized for effecting the delivery 20 of the foam to the top of the oil tank is at times out of proportion to the risk and the value of the property to be protected, and the advantages for such locations of a foam producing system which is operable without auxiliary pressure means such as a pumping system and which is capable of developing sufficient pressure to deliver the foam to high elevations are apparent.

To accomplish the desired object, my present invention comprehends more specifically the provision of an apparatus in which the chemical components for producing the foam are brought into commixing relationship in a manner such as to produce a turbulent or 40 a more or less violent intermixture of the components, this so as to create or generate a maximum quantity of foam of the desired pressure. More particularly, in my present invention an acid tank is provided, and 50 mounted at a level substantially below a basic tank with a connecting line therebetween, the connecting line being so constructed that the basic solution contained in the basic tank is adapted in time of fire to be fed into the acid component contained in the acid tank

with a jet velocity and in a manner to effect the turbulent intermixture of the components; the present invention relating more particularly to improvements in the fire extinguishing apparatus shown in the patent 60 granted to James B. Erwin and myself, No. 1,128,768 of Feb. 16, 1915.

I have found that where the foam is to be delivered to relatively high levels, it is very desirable that the intermixture of the 65 chemical components should be effected in an agitated manner, and in a manner so as to bring a large portion of the components into reaction at the same time. More specifically, I have found that in order to produce the agitated or turbulent commixture, 70 the basic component solution should be bodily introduced into the acid component with a substantial velocity and preferably at a plurality of points, as distinguished from 75 a gentle introduction of the basic solution on the surface of the heavier acid component, the degree of velocity being predetermined to be sufficient to compensate for the difference in specific gravities of the two 80 components and to effect an intimate commixture of the same.

Still further and principal objects of the invention are the provision of an apparatus of the type above referred to in which the 85 parts are co-ordinated to produce a non-freezing system; the provision of a system of this nature which is adapted to be set into operation automatically by the occurrence of a fire and manually by means remote 90 from the fire; and the still further provision of such a system in which the means for automatically and manually operating the system are suitably housed or encased.

To the accomplishment of the foregoing 95 and such other objects as may hereinafter appear, my invention consists in the elements and their relation one to the other, as hereinafter particularly described and sought to be defined in the claims, reference 100 being had to the accompanying drawing which shows a preferred embodiment of my invention and in which:

The figure is a side elevational view of my apparatus showing its attachment to an oil 105 tank, with parts shown in section to disclose the interior construction of the apparatus.

As heretofore mentioned, a prime desideratum of the invention relates to the provision of a fire extinguishing unit in which 110

a basic component solution is fed into an acid component in a manner to effect an agitated intermixture of the components to produce an efficient foam compound capable of rising to high levels. To accomplish this the invention includes the provision of a basic tank 5 adapted for the reception of the B or basic component solution having a composition, for example, as disclosed in the patent to Walker No. 1,186,248, of June 6, 1916, the said tank being mounted at a region elevated relatively to an acid container 6, the tank being connected to the container by means of a solution line 7 which is normally closed and which is adapted to be opened in time of fire for permitting the basic solution to feed through the solution line and into the acid container 6.

The solution line 7 is preferably provided with perforated end pipe sections 8 and 9 respectively, a second perforated pipe section 10 being also provided for a purpose to appear hereinafter, the section 10 communicating with the solution line 7 by means of a by-pass 11. The perforated pipe end 9 extends into the acid container 6, as is clearly shown in the drawings, the perforations or orifices in the pipe section 9 being intended and provided for imparting to the basic solution feeding into the acid container a jet velocity for effecting the desired turbulent intermixture, the perforated end section 9 being extended into the acid container so as to produce a bodily agitation of the acid component to aid in effecting the desired commixture. As a further factor in producing the desired component intermixture, the acid container is spaced from the basic tank so as to provide a substantial gravity head therebetween, and where, as will be referred to hereinafter, the basic tank is intended to provide for a non-freezing apparatus, the jet introduction of the basic component into the acid component permits of decreasing the distance or gravity head between the acid and basic tanks, this enabling the tanks to be buried at a depth less than would otherwise be necessitated.

The container 6 is mounted near the bottom of the pit 12 and within a mixing chamber 13 located at the bottom of the pit, the mixing chamber 13 communicating with a foam conducting means such as a riser pipe 14 extending upwardly and terminating at its upper end in a foam delivery mouth 15 attached preferably to the roof of an oil tank 16, the mouth 15 opening into the tank and above the maximum oil level therein. Although only one foam riser and one extinguishing system is shown associated with the oil tank, it is to be understood that a plurality of such systems may be provided with a single oil tank, it being preferred to provide two or four such systems

arranged in spaced relation circumferentially of the oil tank.

For normally closing the solution line 7, the pipe sections 8 and 10 are provided with valve structures which are adapted to be opened in time of fire to permit the basic solution in the tank 5 to flow gravitationally through the solution line 7 and into the acid container 6, the foam produced in the mixing chamber 13 rising under the pressure developed through the foam riser 14 and discharging into the oil tank through the foam delivery mouth.

For the purpose of equalizing the pressure on the basic solution in the basic tank 5, I prefer to provide an equalizing pipe section 17 connecting the foam riser 14 with the basic tank 5, as is clearly shown in the drawings, this equalizing pipe performing the further function of housing a part of the control means for the system, as will become clearer hereinafter.

The valve constructions used in the pipe sections 8 and 10 may be any known to the art. The pipe sections 8 and 10 may be provided with any suitable valve constructions openable in time of fire to permit the basic solution to flow into the solution line. It has been found, however, that the ordinary valves used in this type of system are oft-times difficult to move, especially in large supply systems, this being many times the case after a long period of inactivity of the device, the valves being corrodible, due to the corrosive effect of the chemical solutions used. To overcome this defect, my invention contemplates the provision of a non-corrodible valve structure in the solution line, the valve being made of fragile material and adapted to be broken in time of fire to permit solution commixture, this type of valve yielding a certainty of operation of the device in emergency events. To this end I have provided a rupturable disk structure shown diagrammatically at 18 and 19; said structure comprising a sealed glass disk shown and described, for example, in my co-pending application, Serial Number 431,921, filed December 20, 1920, the disk 18 being arranged between the pipe section 10 and the by-pass 11 and the disk 19 being arranged between the pipe section 8 and the solution line 7. The said disks normally prevent entry of the basic solution into the solution lines and either or both of the disks are adapted to be broken in time of fire to permit entry of the solution through the solution line and into the vat 6 for the necessary solution commixture.

Means is provided for automatically setting the device in operation in the event of fire, such means in the present form of my invention comprising, for example, a

plunger 20 having at its bottom end a weighted breaker (not shown) and being vertically movable in a spider structure 21 fitted to the tank 5; the said plunger being 5 provided with a head 22 adapted to be struck by a weighted member in the form of, for example, a ball 23, the plunger 22 being normally held in its upward position by means of a spring 24 encircling a portion 10 of the plunger 20. To the weighted ball 23 is connected a counter-weight 27 by means of a control line comprising preferably a chain or a cord such as a bronze cord 25 provided with a plurality of fusible 15 links 28, the cord being trained over a series of pulleys 26 and through the equalizing pipe 17 and part of the foam riser 14, these parts forming a suitable protective casing or housing for the control line 20 to maintain the same against accidental operation and damage. In the event of a fire in the oil tank, the links will be fused, as is obvious, breaking the cord or chain 25, permitting the weighted ball 23 to drop on 25 the plunger head 22, impelling the plunger 20 downwardly for the breaking of the glass seal disk structure 19 to permit the basic solution flow for commixture and foam generation.

30 In the event of failure or inertia of operation of the automatic means described, and for the purpose of further insuring the operability of the device as a whole, means is provided adapted to be manually operated for setting the device into action. To this end I have provided the second glass seal disk structure 18 which is adapted to be broken in time of fire by means preferably of a second plunger 29, vertically 35 movable in spider 30 and being otherwise similar in structure to plunger 20; the said plunger 29 being adapted to be downwardly impelled by the falling of weighted member 31 which is connected to a cord or 40 chain 32, guided preferably through pipe sections 33 and terminating in an eye 34 adapted to be received by a hook 35 mounted in a fire proof box 36. In the event of fire the box is opened, the eye disengaged from its hook and the cord released, permitting the weight 30 to drop and actuate 45 plunger 29 for the breaking of the glass seal disk 18.

50 For the purpose of making the apparatus weather proof and eliminating the disadvantage incident to this type of apparatus of being affected by cold weather, the parts are so arranged and means is provided to 55 secure a non-freezing fire extinguishing system. To this end the basic solution and the basic tank 5 are interred, 37 representing the ground line, the excavated earth being thrown on the tank forming, for example, a mound 38. The acid vat 6 being mounted within the mixing chamber 13

and at the bottom of pit 12, is not openly subject to the elements, but to further insure against the non-freezing of the acid in the vat, such acid may consist, for example, of a 58° Baumé solution of sulphuric acid, such a strength solution having the characteristic of non-freezability. With this arrangement an apparatus is provided which is substantially weather proof, yielding a device which in this respect is certain 75 of operation.

For the purpose of obtaining convenient access to the parts of the apparatus, a man-head 39 may be provided in the basic tank, and the mixing chamber 13 may also be 80 provided with a manhead 40, forming part of the mixing chamber, a permanent ladder 41 being arranged in the pit 12.

The operation of my device will be apparent from the above description thereof. 85 In the event of fire, the glass seal disk 18 or 19 is broken either manually or automatically to permit solution intercommunication between the tank and the vat, and solution commixture in the mixing chamber for the production of a fire extinguishing foam, which moves up the riser pipe 14, due to a number of causes, among which are the pressure of the generated foam, the 90 gravity head of the basic solution, and the foam pressure exerted on the solution level in the basic tank by reason of the conduction of foam from the riser through the equalizing pipe 17 and into the top of the basic tank. The foam moves up the riser pipe and 95 discharges through the foam delivery mouth 15 and into the oil tank, quickly spreading on the top of the burning oil, rapidly extinguishing the same.

100 From the above it will be apparent that I have provided a fire fighting unit especially adaptable for oil fields, but which may 105 obviously be used in other locations, and in which the parts are arranged in a simple manner, the parts being so constructed and means being provided whereby an efficient commixture of the components is obtained to effect 110 the delivery of foam to substantial elevations and whereby a high degree of certainty of operation is obtained, thus yielding a maximum of fire protection for oil fields or the like.

115 While I have shown my device in the preferred form, it will be obvious that many changes and modifications may be made in 120 the structure disclosed without departing from the spirit of the invention, defined in the following claims.

I claim:

125 1. A fire extinguishing apparatus in which component solutions are adapted to be separately stored and to be commixed in the event of fire to produce a fire extinguishing foam, a mixing chamber, a tank holding an acid solution located in said mixing 130

- chamber; a tank holding a basic solution located above said acid solution tank, a duct connecting the said tanks openable in time of fire to permit the basic solution to feed into the acid tank to commix with the acid therein to produce the fire extinguishing foam in said mixing chamber, and equalizing means connecting the mixing chamber and the second mentioned tank.
- 10 2. A fire extinguishing apparatus in which component solutions are adapted to be separately stored and to be commixed in the event of fire to produce a fire extinguishing foam, a mixing chamber, a foam delivery means connected thereto including a riser opening into an oil tank, a tank holding an acid solution located in said mixing chamber, a tank holding a basic solution mounted above the acid tank, a duct connecting the said tanks openable in time of fire to permit solution intercommunication between the tanks and solution commixture to produce the fire extinguishing foam in said mixing chamber, and an equalizing pipe connecting the mixing chamber and the second mentioned tank.
- 15 3. A non-freezing fire extinguishing apparatus comprising an interred tank holding a basic solution, a mixing chamber arranged below the said basic tank having a tank therein holding a non-freezing acid solution, and provisions for commixing the acid and the basic solutions in time of fire to generate a fire extinguishing foam.
- 20 4. In apparatus of the class described, means to deliver a fire extinguishing foam to a tank or the like, comprising a mixing chamber below the level of the tank and provided with a riser for delivering foam thereto, a holding means within the mixing chamber for one of two solutions capable of forming foam when mixed; a holding means for the other of the said solutions at a distance from the chamber and at a higher level and delivering to the holding means in the mixing chamber.
- 25 5. In apparatus of the class described, means to deliver a fire extinguishing foam to a tank or the like, comprising a mixing chamber below the level of the tank and provided with a riser for delivering foam thereto, a holding means within the mixing chamber for one of two solutions capable of forming the foam when mixed, a holding means for the other of the said solutions at a distance from the chamber and at a higher level and delivering to the holding means in the mixing chamber laterally throughout the depth thereof.
- 30 6. In apparatus of the class described, means to deliver a fire extinguishing foam to a tank or the like, comprising a mixing chamber below the level of the tank and provided with a riser for delivering foam thereto, a holding means within the mixing
- chamber for one of two solutions capable of forming the foam when mixed, a holding means for the other of the said solutions at a distance from the chamber and at a higher level and delivering to the holding means in the mixing chamber, means to normally restrain the flow from the last named holding means to the mixing chamber, and temperature controlled means for releasing the restraining means.
- 35 7. In a fire extinguishing apparatus in which component solutions are adapted to be separately stored and to be commixed in the event of fire to produce a fire extinguishing foam, a basic tank for holding a basic component solution, an acid tank for holding an acid component solution located a distance substantially below the basic tank to provide a substantial gravity head therebetween and a normally closed solution line connecting the said tanks having an end extending into the acid tank, the said end being provided with one or more jet producing orifices, the said solution line being openable in time of fire for conducting the basic component into the acid component with a considerable jet velocity due combinedly to the substantial gravity head and the jet producing orifices whereby a turbulent foam producing commixture is effected.
- 40 8. In a fire extinguishing apparatus in which component solutions are adapted to be separately stored and to be commixed in the event of fire to produce a fire extinguishing foam, an interred basic tank for holding a basic component solution, an acid tank for holding a non-freezing acid component solution located below the basic tank, a normally closed solution line connecting the said tanks and having an end extending into the acid tank, the said end being provided with a plurality of jet producing orifices, the said solution line being openable in time of fire for conducting the basic component into the acid component with a considerable jet velocity due to the jet producing orifices for producing a turbulent foam producing commixture, and a foam riser for conducting the foam so produced to a delivery point.
- 45 9. In a fire extinguishing apparatus in which component solutions are adapted to be separately stored and to be commixed in the event of fire to produce a fire extinguishing foam, a basic tank for holding a basic component solution, an acid tank for holding an acid component solution located below the basic tank, a normally closed solution line connecting the said tanks, and mechanism automatically operable on the occurrence of a fire for opening the said line to permit solution commixture, the said mechanism including a control line, means for conducting the foam produced by the solution commix-

ture to a delivery point, and an equalizing pipe connecting the conducting means with the basic tank, the said equalizing pipe and conducting means providing a housing or 5 casing for the said control line.

10. In a fire extinguishing apparatus in which component solutions are adapted to be separately stored and to be commixed in the event of fire to produce a fire extinguishing 10 foam, a basic tank for holding a basic component solution, an acid tank for holding an acid component solution located below the basic tank, and a normally closed solution

line connecting the tanks having an end extending into the acid tank, the said end being provided with one or more jet-producing orifices, the said solution line being openable in time of fire for conducting the basic component into the acid component with a substantial jet velocity whereby a turbulent 20 foam producing commixture is effected.

Signed at New York, in the county of New York and State of New York, this 17th day of December, A. D. 1920.

ORLANDO R. ERWIN.
